Berkley, Mich. 48072

Filed Sept. 10, 1965, Ser. No. 36,937

Term of patent 3½ years

(Cl. D81—10)

FIG. 1

FIG. 2

FIGURE 1 is a front view in elevation of a combined fan and lighting fluid dispenser for a barbecue apparatus showing my new design.

FIGURE 2 is a rear view of the apparatus shown in FIG. 1 with the top plunger extended.

The dominant features of my new design reside in the portions shown in full lines.

I claim:

The ornamental design for a combined fan and lighting fluid dispenser for a barbecue apparatus, as shown and described.
